UNITED STATES PATENT OFFICE.

JOB D. WILKINSON, OF BATTLE CREEK, MICHIGAN.

DIVIDERS OR CALIPERS.

SPECIFICATION forming part of Letters Patent No. 364,561, dated June 7, 1887.

Application filed February 24, 1887. Serial No. 238,724. (No model.)

To all whom it may concern:

Be it known that I, JOB D. WILKINSON, a citizen of the United States, residing at Battle Creek, county of Calhoun, State of Michigan, 5 have invented new and useful Dividers or Calipers, of which the following is a specification.

The object of this invention consists in certain improvements, below described and 10 claimed, with a design to add to the utility and facilitate the operation of dividers or calipers.

In the drawings forming a part of this specification, Figure 1 is an elevation, parts being 15 broken away; Fig. 2, lettered details from Fig. 1, below described, and Fig. 3 is a plan of part A in Fig. 1.

Referring to the lettered parts of the drawings, B B are the ordinary legs of a divider. 20 The curved rack-lever D, with teeth or cogs C, is pivoted at one end in a slot of one of the legs at b, and from thence passes through a slot in the other leg. The latter-named slot s is vertically longer than the width of the rack-lever D, so that the latter can be swung up on 25 its pivot when opening and closing the divider or caliper. The rack D has a shoulder at n, and A is a spring having a free end pressing against said shoulder to hold the rack-lever D 30 down so as to engage the worm C to lock the legs B at desired adjustments. Thus the rack-lever when swung up of disengage the worm C raises against a spring resistance. The free end of the rack-lever has a depressed portion 35 to contact the finger with when raising the rack-lever.

The free end of spring A has an open slot, e, thus making it forked to straddle the rack-lever D back of the shoulder n, thus assisting 40 to keep the spring in place and to hold the rack-lever from lateral canting.

The worm C is journaled to a pin, d, projecting from the leg B just beneath the slot s. In Fig. 2 the pinion is in section, showing the 45 pin d. The main object of this worm C is explained as follows:

Referring to Fig. 1, the divider-legs are separated, we will say, to nearly the desired adjustment. This was quickly effected by raising the rack-lever D, opening the legs at a 50 random guess as to the desired distance, and releasing the rack-lever, which lever the spring A has forced down so that its teeth engage the worm, as before explained.

We will now suppose a fine or accurate adjustment is desired. The legs are a little too 55 far apart, or too near together, as the case may be. By grasping the end a of the worm C with the thumb and finger and turning the worm the legs may be easily and accurately adjusted, 60 even to a hair's breadth, if desired, at the same time the locking-engagement of the rack-lever teeth C' with the worm is preserved during said adjustment.

As above indicated, the invention is equally 65 applicable to calipers or dividers, the construction, aside from the lower portion of the legs, being just the same in both cases. No caliper proper is here shown.

Having thus described my invention, what 70 I claim is—

1. The combination of the slotted legs of calipers or dividers, the rack-lever having the shoulder and pivoted in the slot of one leg, a spring attached to said leg and forming a pressure-contact with said shoulder, and the adjusting-worm pivoted to the other leg, substantially as set forth. 75

2. The combination of the slotted legs, the pivoted rack-lever having the shoulder, the forked spring contacting said shoulder, and the adjusting-worm, substantially as set forth. 80

In testimony of the foregoing I have hereunto subscribed my name in presence of two witnesses.

JOB D. WILKINSON.
